US00D841231S

(12) **United States Design Patent** (10) **Patent No.:** **US D841,231 S**
(45) **Date of Patent:** **** Feb. 19, 2019**

(54) **ELECTRONIC VAPING DEVICE MOUTHPIECE**

(71) Applicant: **Altria Client Services LLC**,
Richmond, VA (US)

(72) Inventors: **Eric Hawes**, Glen Allen, VA (US); **Ali Rostami**, Glen Allen, VA (US)

(73) Assignee: **Altria Client Services, LLC**,
Richmond, VA (US)

(**) Term: **15 Years**

(21) Appl. No.: **29/554,552**

(22) Filed: **Feb. 12, 2016**

Related U.S. Application Data

CLAIM

The ornamental design for an electronic vaping device mouthpiece, as shown and described.

DESCRIPTION

FIG. 1 is a right perspective view of the electronic vaping device mouthpiece;

FIG. 2 illustrates an end elevation view of the electronic vaping device mouthpiece of FIG. 1;

FIG. 3 illustrates a top plan view electronic vaping device mouthpiece of FIG. 1, the bottom plan view being a mirror image; and,

FIG. 4 is a cross-sectional view, taken along line 4-4 shown in FIG. 2, of the electronic vaping device mouthpiece of FIG. 1.

The dash-dash broken lines in the drawings depict the environment in which the electronic vaping device mouthpiece is used and form no part of the claimed subject matter. The dash-dot-dash broken lines in the drawings depict the bounds of the claimed subject matter and form no part of the claimed design.

1 Claim, 4 Drawing Sheets
